UNITED STATES PATENT OFFICE.

EDWARD C. GLEDHILL, OF GALION, OHIO. ASSIGNOR TO THE GALION IRON WORKS
AND MANUFACTURING COMPANY, OF GALION, OHIO.

UNLOADING DEVICE.

1,105,131.

Specification of Letters Patent.

Patented July 28, 1914.

Application filed January 9, 1913. Serial No. 741,031.

To all whom it may concern:

Be it known that I, EDWARD C. GLEDHILL, citizen of the United States, residing at Galion, in the county of Crawford and State 5 of Ohio, have invented certain new and useful Improvements in Unloading Devices, of which the following is a specification.

My invention relates to new and useful improvements in systems for unloading and 10 storing coal, crushed rock, gravel, sand or other loose cargoes from cars and the object of my invention is to provide a system by which said cargo may be expeditiously and conveniently handled.

15 A further object of my invention is to provide in connection with a car track having bins formed between the rails to receive the cargo discharged through the swinging bottoms of the cars, a portable storage bin movable in spaced relation to the track and having an inclined track leading from the bin 20 along which a bucket or container is movably mounted.

25 A further object of my invention is to provide means for discharging coal from the bin into the bucket to fill the same, for raising the bucket along its tracks and for then discharging the contents of the bucket into the storage bin.

30 A further object of my invention is to provide means for automatically controlling the loading and unloading of the bucket.

With these and other objects in view, my 35 invention will be more fully described, illustrated in the accompanying drawings, and then specifically pointed out in the claims which are attached to and form a part of this application.

In the drawings: Figure 1 is an elevational view, partially in section, showing the 40 improved system in operation; Fig. 2 is a fragmentary elevation upon an enlarged scale, showing the arrangement of pulleys upon the storage bin for the hoisting cables; Fig. 3 is a fragmentary top plan view of the 45 structure shown in Fig. 2; Fig. 4 is a vertical sectional view taken through a modified form of cargo handling bucket; Figs. 5 and 6 are fragmentary side elevations, showing 50 the manner in which the bucket itself, during its movement, controls the gate governing the discharge from the bins between the rails to the bucket.

Corresponding and like parts are referred

to in the following description and indicated 55 in all the views of the drawings by the same reference characters.

My improved invention, in its simplest form, is clearly illustrated in Fig. 1 in which the railroad track is shown in section, 60 the rails 10 of the track being supported in the usual manner upon spaced ties 11. Bins 12 are formed immediately below the ties and between the rails of the track, extending at one end beyond the side of the track, 65 as shown. These bins preferably all communicate with each other at their lower ends and are provided with an inclined bottom 13, preferably formed of metal. At the outer end of the bin, is a pair of spaced 70 guides 14 in which is slidably mounted a plate 15 forming a gate. The coal, crushed stone or other cargo of a car is emptied into these bins through the dumping bottom of the car in the usual well known manner, the 75 car being conventionally shown at 16 and a portion of its cargo in the bin at 17.

The bin beyond the gate 14 is deepened as shown at 18 and provided with an upwardly and outwardly inclined outer wall 19, this 80 deepened portion of the bin permitting the positioning of a cargo-carrying-bucket at a level below that of the lower end of the inclined bottom 13 of the bin proper in such a position that upon the raising of the gate 85 15, the material contained in the bin 12 will slide along the bottom 13 and into the bucket to load the same.

A movable storage bin, indicated as a 90 whole by the numeral 20, includes a supporting frame 21 mounted upon wheels 22 in such a manner that it may be moved in parallel spaced relation to the track to bring it opposite the various portions of the bin and this frame carries the substantially rectangular shaped bin adapted to receive and store the coal or other cargo, the bin being provided at one side with a discharge chute 23 having a swinging gate 24 adapted when held in normal position by a latch 25 to 95 prevent discharge of the contents of the bin. Any suitable form of prime mover, such as a gas engine is also carried by the frame 21, such an engine being shown at 26 and this engine is not only adapted to raise and 100 lower the bucket to convey the coal from the delivery bin to the storage bin, but may be also arranged to drive the storage bin itself,

if desired, although this latter construction, as it forms no part of my invention, is neither illustrated nor described.

Extending upward from the inner upper portion of the bin, is a frame 27 having suitable braces 28 and mounted upon the forward portion of this frame, preferably upon a common shaft 29, are a pair of spaced pulleys 30 and 31. This shaft 29 may be journaled in a bracket 32 which also carries a vertically disposed shaft 33 upon which is mounted a pulley 34, the latter pulley being disposed at the rear and intermediate of the pulleys 30 and 31. Another pulley 35 is mounted upon the frame 21 adjacent the shaft of the engine 26 and a cable 36 is secured by one end to a winding drum 37 carried by the engine shaft and the other end of this cable is passed upwardly over the pulley 35, rearwardly over the pulley 31 and about the pulley 34 and forwardly and downwardly over the pulley 30, being secured at its free end to a hook 38 for engagement with the swinging bail 39 of the cargo carrying bucket 40.

Extending from the forward upper portion of the bin, are angularly formed brackets 41 to which are secured spaced tracks 42 of angle iron, forming an inclined support for the bucket 40, the lower ends of these angle iron tracks extending to the bottom of the deepened portion 18 of the bin 12 while the upper ends are curved outwardly to rest upon the top of the bin 20, which top is open. These angle iron tracks are so disposed as to provide vertical track flanges and inwardly directed horizontal track flanges, and the bucket is mounted to move upon the horizontal flanges and to be guided and held in place between and by the vertical flanges. As shown, the outer face of the bucket is inclined to correspond to the inclination of the track and as clearly illustrated by the dotted lines in Fig. 1, the bail 39 is so attached to the bucket that when the latter is unsupported at its upper end by the track, the bucket being supported wholly by the bail and cable, the bucket will be tilted to discharge its contents. Because of this construction, the bucket when raised to the top of the track, will automatically tilt to discharge its contents into the bin.

In operation, the coal or other cargo to be handled is discharged into the main bin 12, the gate 14 being closed and the storage bin 20 is moved into position adjacent said portion of the track. The bucket 40 is then lowered into position to receive a portion of the cargo contained in the pit or bin 12 and the gate 15 raised a suitable distance to permit the coal or other material to run into and fill the bucket, to which said gate is then closed. The engine is then started to wind up the cable until the bucket reaches the top of the track when it is automatically

discharged in the manner described. The engine is then reversed to lower the bucket and the operation continued until all the coal has been transferred from the bin 12 to the storage bin 20.

In order to prevent the bucket from moving downwardly too rapidly and also in order to lessen the power needed to raise the bucket when loaded, one of the braces 28 may be provided with a bracket 43 carrying a pulley 44 and a second cable 45 may be secured by one end to the hook 38, passed about an additional pulley 46 carried by the pulley bracket 32 and rearwardly and downwardly over the pulley 44, being connected at its free end to an adjustable weight 47. This weight should be so adjusted as to nearly, but not quite, counterbalance the weight of the bucket when empty and it will therefore be apparent that the bucket, when emptied, will move slowly down the inclined track and that when filled the engine need lift but a little more than the weight of the bucket's contents, the counterweight 47 being nearly heavy enough to raise the bucket.

If desired, a bucket of the type shown in Fig. 4 of the drawings may be employed in place of the bucket 40. This bucket, indicated as a whole by the numeral 48, is similar in shape and size to the bucket 40 but is provided with an inclined bottom 49 and in its outer wall with a swinging closure 50 hinged to the wall proper by a hinge 51 and normally held in closed position by a resilient latch 52 secured to the lower face of the bottom 49. A spring 53 of sufficient strength to swing the closure 50 to operative position when the bucket is empty, is secured upon the bucket and the resilient latch 52 is provided with an upper inclined face over which the lower edge of the closure may ride while swinging to closed position.

In order to provide for automatically discharging the contents of the above described type of bucket when employed in my cargo handling system, a trip rod or bar 54 is extended transversely between the tracks 42 near their upper ends in position to engage the latch 52 and swing the same out of engagement with the door or closure 50. It will of course be apparent that the weight of the coal or other material contained in the bucket will be sufficient to swing the door to open position when so released and to hold the same open until the cargo is discharged. As soon as the bucket has been emptied, the spring 53 will immediately swing the door to closed position and the bucket may then be lowered.

In Figs. 5 and 6 of the drawings I have illustrated a modified form of automatic chute for use in the bin 12 by means of which the cargo conveying bucket 40 or the

bucket 48, shown in Fig. 4, may be automatically loaded. This automatic chute takes the place of the gate or closure 15 and comprises a main body or chute 55 provided at 5 its free end with an extension 56 which is pivotally connected to the main body, as shown at 57 in such a manner that it may be swung upwardly at right angles to the main body to form a closure therefor or down- 10 wardly in alinement with the main body to form a continuation thereof and assist in the discharging of the coal or other contents of the bin. The sides of the chute 55 are provided in their upper faces with 15 notches or seats 58 adapted to receive the free end of a pivoted catch 59 carried by the extension 56 of the chute and to normally hold the said extension in raised position, the catch 59 being held in engagement, 20 against the upper faces of said sides by springs 60.

Pivoted by means of upwardly extending ears 61 formed one upon either side of the body portion, is a trip member 62, the body 25 portion of which extends downwardly into the bin 18 in such a position as to be engaged and swung rearwardly by the bucket during the downward movement of the latter, this trip member being normally held 30 in forward position by a spring 63. The ears 61 of this trip member carry arcuate fingers 64 which in normal position of the gate or chute extension 56 and trip member 62 engage against the lower faces of the 35 latches 59, as shown in Fig. 5 of the drawings.

Upon lowering the bucket 40 or 48, as the case may be, said bucket passes by the extension 56 of the chute and engages the trip 40 lever and swings the same rearwardly and this swinging of the trip member acting through its fingers 64 to release the latches 59 and permit the downward swinging of the extension 56 of the chute, this swinging 45 being caused by the pressure of the coal or other material in the bin. When the bucket has become nearly full, the engine is started to raise the same and during its upward movement, the bucket engages the chute ex- 50 tension 56 to raise the same until it is locked in its original position by the latches 59, thus cutting off all further escape of coal or other material from the bin. Upon the raising of the bucket, the trip member 62 is 55 swung forward again by its spring and the device is again ready for operation.

It will therefore be seen that when the system is equipped with the chute structure shown in Figs. 5 and 6, the entire unloading

and storing of the cargo may be accom- 60 plished by a single person, this person operating the engine and manipulating the one or two levers required to control the action of the winding drum.

The above described cargo handling sys- 65 tem is therefore not only simple and efficient, but also inexpensive in operation.

It will of course be understood that I do not wish in any way to limit myself to the specific details of construction illustrated in 70 the drawings and described in the above specification, as any changes in details of construction, found desirable, may at any time be made without in the slightest degree departing from the spirit of my invention as set forth in the appended claims.

Having thus described the invention, what is claimed as new is:

1. A cargo handling system including an inclined track, a bucket movable along the 80 track, a chute directed toward the lower portion of the track, an extension swingingly mounted upon one end of the chute, a spring pressed pawl carried by the extension and engaging the chute to normally hold the extension in position to prevent the passage of material through the chute, a swinging member mounted upon the extension and projecting into the path of the bucket, and a pawl engaging finger carried 85 by said member and arranged to release the pawl when said member is engaged by the bucket.

2. A cargo handling system including an inclined track, a bucket movable along the 95 track, a chute directed toward the lower portion of the track, an extension swingingly mounted upon one end of the chute, a spring pressed pawl carried by the extension and engaging the chute to normally hold the extension in position to prevent the passage of material through the chute, a swinging member mounted upon the extension and projecting into the path of the bucket, and a pawl engaging finger carried 100 by said member and arranged to release the pawl when said member is engaged by the bucket, said chute extension, upon release, 105 projecting in the path of the bucket upon its return, whereby the bucket raises the extension to close the chute.

In testimony whereof I affix my signature in presence of two witnesses.

EDWARD C. GLEDHILL. [L.S.]
